UNITED STATES PATENT OFFICE.

JAMES DALLAS COLLIER AND JAMES K. POLK MILLER, OF WOODVILLE, TEXAS, ASSIGNORS OF ONE-THIRD TO JOHN H. KIRBY, OF SAME PLACE.

ELECTRICAL CONNECTION AND SIGNAL FOR RAILWAY-CARS.

SPECIFICATION forming part of Letters Patent No. 462,794, dated November 10, 1891.

Application filed March 25, 1891. Serial No. 386,346. (No model.)

To all whom it may concern:

Be it known that we, JAMES DALLAS COLLIER and JAMES K. POLK MILLER, citizens of the United States, residing at Woodville, 5 in the county of Tyler and State of Texas, have invented certain new and useful Improvements in Electrical Connections and Signals for Railway-Cars; and we do hereby declare the following to be a full, clear, and 10 exact description of the invention, such as will enable others skilled in the art to which it appertains to make and use the same.

Our invention relates to the application of electricity to suitable electrically-operated 15 devices throughout a train, such as electrically-operated signals, electrically-controlled brakes and car-couplings, and other devices which may be operated or controlled by electricity; and it consists in suitably-controlled 20 and reversible electric circuits extending throughout the train, and in such other devices as will be hereinafter described and claimed.

Reference is had to the accompanying drawings, 25 wherein the same parts are indicated by the same letters.

Figure 1 represents a plan view of the lower portions of a car, the floor of the car and various other parts being removed to better illustrate the operation of our invention. The secondary wires are also represented as symmetrically spread out in the center of the car. Fig. 2 represents a horizontal section through the car-coupler and the two sections of our 30 electric couplers connected to each end of the car. Fig. 3 represents an end view of one-half of our electric coupler. Figs. 4 and 5 represent two systems of electric connections in a train, being diagrammatic views of two systems 35 adapted for use with the apparatus shown in Fig. 1. Fig. 6 represents a form of reversing-key adapted to be used with the systems shown in Fig. 5. Fig. 7 represents a plan view of a circuit-testing device.

40 Although a number of broken circuits connected to one single return-wire would ordinarily be sufficient, yet to make connections adapted to the condition that either end of the car may be shifted next to the locomotive or 45 to the source of electricity we have found it necessary to employ either one electric-wire

coupler in the center of the car, in which case the mechanical difficulties as well as the danger of short-circuiting would be great, or two electric-wire couplers on either side of the car 55 with the current passing through one and returning via the other. In the latter case there will be necessary either a means of shifting the current or a double system of wires in each car.

6c

In this application we will describe the use of two electric contact-making couplers, one on either side of the draw-head of the car. These couplers are each connected to a main conductor running through the train and by 65 branching wires to one central series of wires also running throughout the train.

The source of electricity may be carried anywhere in the train, (preferably the main source of electricity should be located on the 70 locomotive-tender,) and there may be separate auxiliary sources of electricity on each car for use when the locomotive is not attached to the train.

We have shown the main source of electricity at E on the tender and auxiliary sources E' E², &c., on the various cars. Connected to the poles of the source of electricity are two large wires or mains a and a', running throughout the train and connected from car to car 80 by the circuit-couplers B and C. In each car we also have a series of smaller wires a² a³ a⁴, &c., all branching at the two ends of the car and having the two branches connected to symmetrical contact-strips b² b³ b⁴, &c., c² 85 c³ c⁴, &c., on the circuit-couplers. These circuit-couplers consist of a male coupler C and a female coupler B, which may be secured to the body of the car in any way; but we prefer to connect them to the draw-head F of the 90 car-coupler by angle-irons or brackets D and D'. By this means the spring attached to the base of the car-coupler co-operates with the springs on the circuit-couplers to lessen the effect of the vibrations in the cars. The body 95 of these circuit-couplers is of insulating material, and the two faces in contact have a number of contact-strips b² b³ b⁴, &c., c² c³ c⁴, &c., made of elastic metal, &c., each connected to its proper wire. Moreover, the two 100 parts of the circuit-coupler are kept in close contact by means of a spiral spring G, at-

tached to the base of either half of the circuit-coupler. We have shown it as attached to the base of the female portion; but it may be attached to either or to both equally well.

5 We preferably make the male circuit-coupler in the form of the frustum of a truncated quadrangular pyramid, when, owing to the wedge shape of C, it will slide into and be centered by B. At each corner of the top of 10 C we have four metallic contact-strips c^5 c^6 , &c., which press against the contact-strips b^5 b^6 , &c., similar in other respects to b^1 b^2 b^3 , &c., both c^5 and b^5 being connected each to a corresponding wire and four circuits to our 15 system.

In the center of either all the male couplers or of all the female couplers, as shown, we have a metallic plunger B', pressed out by a spiral spring at its base, and making contact with a plate we have connected to the large central wire of each group, and this connection forms the return-circuit for all the wires of the opposite group. Attached to the base of this plunger we have a contact-maker, 20 which completes the circuit and sounds an alarm when any of the cars become uncoupled or break loose, as shown in our applications, Serial Nos. 380,150 and 381,858.

The two mains a and a' lead from their respective poles of the sources of electricity to the centers of the two circuit-couplers, and are thus connected from car to car throughout the train. The other wires are each well insulated and in one series A inclosed in a 35 flexible insulating-pipe H, preferably rubber. These wires branch at the two ends of the car into symmetrical divisions A' and A'', each connected to symmetrical contact-pieces on their respective circuit-couplers.

40 In order to obtain good electrical connection between the wires a^2 a^3 , &c., and their branches, the said wires a^2 a^3 , &c., may be made of two wires twisted together before insulation and then having the two wires thus 45 twisted together separated near the end of the car and connected to appropriate contact-strips on their respective circuit-couplers. These wires are not directly connected to any of the sources of electricity, but are so arranged that they can individually be made to complete the circuit through the mains a and a' . This is illustrated in Figs. 4 and 5, where we have represented, in addition to the mains, a series of three central signal-wires, 50 branching at their ends to connect with both circuit-couplers. In Fig. 4 we have also shown the connections in three cars, the central car being turned end for end.

In Fig. 4, a^2 , a^3 , and a^4 represent three of 55 any desired number of wires running throughout the train and connected from car to car by symmetrically-arranged contact-pieces on the various circuit-couplers. These wires are not directly connected to any of the sources of electricity, but are provided with suitable circuit-closers (shown as push-buttons k^2 , k^3 , and k^4) to close a circuit between the mains

a and a' . In each of these circuits I inclose some electric signal (an alarm-bell or electric indicator, &c.,) m^2 m^3 m^4 , &c., so that the current coming from a passes through the circuit-closer (say k^3) to the wire a^3 , and from this, passing through the signal m^3 and wire w , flows along a' back to the opposite pole of the source of electricity.

75 It will be seen that were there one continuous main on one side of the train and a continuous return-main on the other side of the train, with circuit-closers, signals, &c., all similarly arranged, as in cars I and III, Fig. 4, that a current passed through any one button, as k^3 , would course along the wire a^3 and make the signal m^3 in each car; but if one or more of the cars should get shifted end for end, as in car II, Fig. 4, then some reversing 80 device will be necessary, for in car II, if connection is made, as shown in dotted lines at a^x and $a^{x'}$, then when k^3 in car I is closed the signal m^3 in car I would be made; but the signals in the other cars being connected to the same pole of the battery as the wire a^3 would feel no current, and hence would be silent; but by introducing reversing-keys at 85 N with connections, as shown, closing any circuit in any one car, corresponding signals 90 in each car throughout the train would be made.

In Fig. 5, where the reversing-key shown in Fig. 6 is used, instead of reversing the current through the mains a and a' the mains 100 are continuous from car to car, while the current is reversed in the branch wires w' and w'' , connected to the system of circuit-closers and the system of signals, respectively. In order to determine whether the reversing-key 105 is in the proper position, we provide a test-key t , connected to a galvanometer t' . This galvanometer is shown enlarged in Fig. 8. When the connections are properly made, upon pressing t the needle t' will be deflected to the right and the "O. K." marked at the side of the galvanometer will show the brakeman that the connections are all right. When the connections are not properly made, upon pressing t the needle will be deflected to the 110 left and the key N should be shifted. The key t will also give information that the various parts of the main circuits are in electrical connection. This key and a number of signals may all be placed on a small indicator-board. After coupling on each new car the circuit in 115 the car should be tested, and once the connections are properly made they will require no further attention.

120 It will readily be seen that by our system signals may be made either by indicator, bell, telegraph, or telephone, or that brakes or couplings or other electrically-controlled devices may be operated.

Fig. 1 shows a system of brakes and part of 125 a coupling system adapted to be used with our system of connections. Thus we may apply brakes by a connection similar to that shown with the signal-bell, the electricity

being made to flow through a solenoid connected to a toggle-joint and having its armature also connected to a toggle-joint, the said toggle-joints being connected to the ends of 5 the brake-beams and pressing the brake-shoes against the car-wheels when the armature is drawn to the solenoid, as when a current is passing therethrough. This particular form of brake mechanism is fully described 10 and is claimed in our application, Serial No. 380,150. We may also couple and uncouple any car in the train by closing a circuit and making a similar solenoid and its armature raise or release a coupling-link by means of 15 a rock-shaft and a suitable system of levers connected to the said armature and put into operation by passing a current through the said solenoid. The form of electrically-operated device for accomplishing this coupling 20 or uncoupling is fully described and is claimed in our application, Serial No. 381,858. We may also use our system of conductors with any other electrically-operated device to which it may be adapted; also, it is evident 25 that the number of wires and the combinations of those wires may be increased indefinitely and the corresponding number of signals or other uses to which the electric fluid may be put may be similarly increased.

30 In applying brakes it would be advisable to get the combined force of all the sources of electricity in the train, which could readily be done by a current closing all the open switches $O' O^2$, &c., and applying the electricity of the storage-batteries $E' E^2$, &c., to the brake-circuit in addition to the current from the main source E .

In signaling it would be advisable to use only a part of the main current or to use 40 a storage-cell or a galvanic battery in any part of the train. It will also be seen, when part of the train becomes detached from the main source of electricity, that by closing O' any one car may at once furnish the source 45 of electricity for signaling purposes, or by closing all the brakes $O' O^2$, &c., as already suggested, that the combined effect of all the auxiliary batteries on the train may be obtained. One or all of these brakes may be 50 closed by the automatic plunger described in our applications filed February 4, 1891, and February 18, 1891, Serial Nos. 380,150 and 381,858, or in a variety of ways.

It will be obvious that many modifications 55 would readily suggest themselves to any one skilled in the art, which could be used without departing from the spirit of our invention.

What we claim, and desire to secure by Letters Patent of the United States, is—

1. In a railway-train, the combination, with a source or sources of electricity, of two main wires connected to opposite poles of the source of electricity leading throughout the train and 65 electrically connected from car to car by circuit-couplers on either side of the draw-head, a series of secondary wires branching at either

end of the car and symmetrically connected from car to car by the said circuit-couplers, each of said wires being connected to one of 70 the mains and to a device operating by electricity, and a series of circuit-closers attached to the opposite main and capable of connecting the secondary wires therewith, substantially as described.

2. In a railway-train, the combination, with a source or sources of electricity, of two main wires connected to opposite poles of the source of electricity leading throughout the train and electrically connected from car to car by 80 circuit-couplers on either side of the draw-head, a series of secondary wires branching at either end of the car and symmetrically connected from car to car by the said circuit-couplers, each of said wires being connected 85 to one of the mains and to a device operating by electricity, a series of circuit-closers attached to the opposite main and capable of connecting the secondary wires therewith, and a reversing-key in each car for reversing 90 the current in said car, substantially as described.

3. In a railway-train, the combination, with a source or sources of electricity, of two main wires connected to opposite poles, of the source 95 of electricity leading throughout the train and electrically connected from car to car by circuit-couplers on either side of the draw-head, a series of secondary wires branching at either end of the car and symmetrically connected 100 from car to car by the said circuit-couplers, each of said wires being connected to one of the mains and to a device operating by electricity, a series of circuit-closers attached to the opposite main and capable of connecting 105 the secondary wires therewith, and a reversing-key in each car located in a secondary wire for reversing the current in the said secondary wires in said car, substantially as described.

4. In a railway-train, the combination, with 110 two mains electrically connected throughout the train, of a wire a^3 , also electrically connected throughout the train, the electrically-operated device m^3 , connected to the said wire a^3 and to one main, the circuit-closer k^3 , 115 connected to the said wire a^3 and to the opposite main, and a reversing-key N for reversing the connections when the cars are shifted end for end, substantially as described.

5. In a railway-train, the combination, with 120 two mains electrically connected throughout the train, of the wire a^3 , also electrically connected throughout the train, the electrically-operated device m^3 , connected to the said wire a^3 and to one main, the circuit-closer k^3 , 125 connected to the said wire a^3 and to the opposite main, a reversing-key N for reversing the connections when the cars are shifted end for end, and a test-key t and galvanometer t' , substantially as described.

6. In a railway-train, the combination, with a source of electricity in each car, of two mains extending through the train and suitable circuit-closers connecting said mains 130

with one or all of the said sources of electricity, a series of secondary wires a^2 a^3 a^4 , &c., electrically connected from car to car throughout the train, the electrically-operated devices m^2 m^3 m^4 in each car connected to the said secondary wires and to one main, the circuit-closers k^2 k^3 k^4 in each car connected to the said secondary wires, respectively, and to the opposite main, and a reversing-key in each car for reversing the circuit through the said circuit-closers and electrically-operated devices when the car is shifted end for end, substantially as described.

7. In a system of signals for railway-trains, the combination, with a source of electricity carried by or connected to the train, of two mains a and a' , electrically connected through-

out the train, a series of wires a^2 , a^3 , and a^4 , also electrically connected throughout the train, an electric signaling device connected to each of said wires and to one main, a circuit-closer connected to each of said wires and to the opposite main, a test-key t , connecting the said mains, and a reversing-key N in each car for reversing the circuit when the car is shifted end for end, substantially as described.

In testimony whereof we affix our signatures in presence of two witnesses.
